STEREO PHONOGRAPH UNIT OR SIMILAR ARTICLE

William T. Allan, 4264 Thornton Ave.,
Fremont, Calif. 94536

Filed Dec. 13, 1967, Ser. No. 9,765
Term of patent 14 years

U.S. Cl. D56—4
Int. Cl. D14—01; D14—03

FIG. 1

FIG. 2

FIG. 3

FIG. 4

FIGURE 1 is a front elevational view of a stereo phonograph unit or similar article, showing my new design;

FIGURE 2 is a top plan view;

FIGURE 3 is a bottom plan view; and

FIGURE 4 is a right side elevational view, the opposite side being substantially a mirror image thereof.

I claim:

The ornamental design for a stereo phonograph unit or similar article, substantially as shown and described.
